UNITED STATES PATENT OFFICE.

HARRY A. COOK, OF DIXON, NEBRASKA.

INSULATOR.

1,169,011.

Specification of Letters Patent. Patented Jan. 18, 1916.

Application filed September 26, 1914. Serial No. 863,729.

To all whom it may concern:

Be it known that I, HARRY A. COOK, a citizen of the United States, residing at Dixon, in the county of Dixon and State of Nebraska, have invented certain new and useful Improvements in Insulators; and I do hereby declare the following to be a full, clear, and exact description of the invention, such as will enable others skilled in the art to 10 which it appertains to make and use the same.

This invention relates to insulators employed in holding telephone or telegraph line wires and the primary object of the invention is the provision of a reinforced glass insulator which will materially decrease the liability of the breaking of the insulator.

Another object of this invention is the provision of an insulator which has molded 20 therein a foraminous metallic sheet or plate, whereby the insulator will be materially strengthened and the liability of breaking the insulator such as by boys throwing rocks and striking the same will be reduced.

25 A still further object of this invention is to reinforce an insulator so as to prevent short circuit caused by the insulators being broken which releases the tie wires and allows the telephone wires to drop on other 30 wires, and to insert within the body of the non conductive insulator reinforcing metal for holding tight the various parts of the insulator and preventing the same from falling to pieces when cracked thereby eliminating the liability of short circuit as above 35 mentioned.

With the foregoing and other objects in view this invention consists in such novel features of construction, combination and 40 arrangement of parts as will be hereinafter more fully described, illustrated in the accompanying drawings and claimed.

In describing the invention in detail reference will be had to the accompanying drawings 45 wherein like characters designate like or corresponding parts throughout the several views and in which:

Figure 1 is a side elevation of the improved insulator. Fig. 2 is a bottom plan 50 view of the insulator. Fig. 3 is a cross sectional view through a modified form of the insulator, and Fig. 4 is a cross sectional view on the line 4-4 of Fig. 3.

Referring more particularly to the draw-

ings, 1 designates the body of the insulator which is constructed of glass or other analogous material and has secured to the lower end thereof a bell or water shed 2. The body 1 of the insulator is provided with an annular groove or recess 3 extending entirely about the circumference of the same a short distance downwardly from its upper end, and also with a second groove 4 which extends about substantially one-half of the under surface of the insulator. The groove 4 has seated therein a tie wire 5, which tie wire extends interiorly into the insulator body 1 through openings 5' and is connected in any suitable manner to the metallic reinforcing sheet or plate 6.

In Figs. 1 and 2 of the drawings, the metallic reinforcing strip is shown as wire netting, and it is molded in the body 1 of the insulator, for strengthening the insulator and preventing the same from becoming broken by boys throwing stones against it or other accidents. The body 1 of the insulator has an internally screw threaded opening 7 formed therein, which receives the upper reduced end 8 of the supporting post 9, which is secured to the cross arm 10 of an ordinary telephone line wire supporting post (not shown).

In Fig. 4 of the drawings a modified form of the insulator is shown, which comprises a glass body 20 which has molded therein a cup shaped member 21. The cup shaped member 21 is formed of sheet metal, and it has a plurality of tongues 22 formed thereupon, which are provided for engaging the glass or other analogous material of which the insulator body 20 is formed, for securely holding the cup shaped reinforcing member 21 in its proper position within the insulator. The body 20 also has a groove 23 formed annularly therein, which groove is provided for attachment to the insulator of an ordinary tie wire such as is at present used. The insulator 20 has a tie wire secured thereto which is similar to the tie wire 5' as illustrated in Fig. 1 of the drawings. This tie-wire 24 is securely connected in any suitable manner to the cup-shaped reinforcing member 21.

In reducing the invention to practice certain minor features of construction, combination and arrangement of parts may necessitate alterations to which the patentee is

entitled provided such alterations are comprehended within the scope of what is claimed.

What is claimed is:—

- 5 1. In an insulator structure, an insulator body constructed of glass and having a metallic cup shaped reinforcing member molded within the body of the insulator for strengthening the same, and tie wires carried by said insulator body and connected to said metallic reinforcing member.
- 10 2. In an insulator structure, an insulator body constructed of glass, a metallic rein-

forcing member molded within said insulator, said metallic reinforcing member having a plurality of tongues formed thereupon for engagement with the glass, and tie wires secured to said metallic reinforcing member and projecting out of said insulator body.

In testimony whereof I affix my signature 20 in presence of two witnesses.

HARRY A. COOK.
